(57) **CLAIM**

The ornamental design for a portable diaper changing apparatus, as shown and described.

DESCRIPTION

FIG. 1 is a top plan view of a portable diaper changing apparatus showing my new design;

FIG. 2 is a bottom plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view showing the present invention at a folded position.
